US0D1062731S

(12) **United States Design Patent** (10) **Patent No.:** **US D1,062,731 S**
(45) **Date of Patent:** **** Feb. 18, 2025**

(54) **DATA PROCESSING MONITOR**

(71) Applicant: **LG ELECTRONICS INC.**, Seoul (KR)

(72) Inventors: **Hyeongyeol Kim**, Seoul (KR); **Daihyung Ryu**, Seoul (KR); **Sharim Choe**, Seoul (KR)

(73) Assignee: **LG ELECTRONICS INC.**, Seoul (KR)

(**) Term: **15 Years**

(21) Appl. No.: **35/518,466**

(22) Filed: **Mar. 29, 2023**

(80) **Hague Agreement Data**

Int. Filing Date: **Mar. 29, 2023**

Int. Reg. No.: **DM/228083**

Int. Reg. Date: **Mar. 29, 2023**

Int. Reg. Pub. Date: **Sep. 29, 2023**

(30) **Foreign Application Priority Data**

Oct. 4, 2022 (KR) 30-2022-0040580

(51) **LOC (15) Cl.** **14-02**

(52) **U.S. Cl.**

USPC **D14/374**

(57) **CLAIM**

The ornamental design for a data processing monitor as shown and described.

DESCRIPTION

1. Data processing monitor

1.1 : Front perspective view

1.2 : Rear perspective view

1.3 : Front

1.4 : Rear

1.5 : Left

1.6 : Right

1.7 : Top

1.8 : Bottom

1.9 : Enlarged view of portion “1.9” of Reproduction 1.5

1.10 : Enlarged view of portion “1.10” of Reproduction 1.6

1.11 : Enlarged view of portion “1.11” of Reproduction 1.7

The even-dash broken lines indicate portions of the article that form no part of the claimed design. The dot-dash broken lines indicate the boundaries of the enlarged views and form no part of the claimed design.

1 Claim, 11 Drawing Sheets
